UNITED STATES PATENT OFFICE.

CHARLES KNAUER, OF PLYMOUTH, WISCONSIN.

FEED-CUTTER.

SPECIFICATION forming part of Letters Patent No. 319,492, dated June 9, 1885.

Application filed May 10, 1884. (No model.)

To all whom it may concern:

Be it known that I, CHARLES KNAUER, a citizen of the United States, residing at Plymouth, in the county of Sheboygan and State 5 of Wisconsin, have invented certain new and useful Improvements in Feed-Cutters; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to that class of feed-cutters in which, with knives cutting intermittently, it is desirable to have the material for cutting delivered to the knives intermittently.

20 The object of my invention is twofold: first, in a feed-cutter to secure the forward or delivery movement of the straw or stalks to be cut intermittently at the moment when the knife is removed from contact therewith. 25 This I accomplish by the usual feed-rollers operated by my improved mechanism, consisting of a spur-wheel affixed to one of said rollers and worked by an intermitting worm-wheel attached to a power-shaft revolving at right 30 angles to such rollers; second, to reduce and, as far as possible, avoid the friction heretofore met with in the use of worm-wheels, which I accomplish by putting loosely-fitting revolving sleeves about the cylindrical teeth of the 35 spur-wheel, thereby obviating the friction heretofore experienced, caused by the rubbing or sliding of the teeth of the spur-wheel against the sides of the channels of the worm-wheel.

40 Referring to the drawings herewith, Figure 1 represents a view of my mechanism attached to a feed-cutter. Fig. 2 is a vertical sectional view of the spur-wheel, showing the teeth with loosely-fitting revolving sleeves. Figs. 3 and 4 are views of two varieties of worm-wheels, 45 whereby by the use of one or the other I obtain greater or less forward movement or feed of the material, as desired.

Like letters refer to the same parts in all the views.

50 Referring to the drawings, A is the side and frame of a feed-cutter box. B is a wheel to which the revolving cutting-knives are affixed,

which wheel revolves vertically in front of the open front end of the cutter-box. The wheel C is rigidly affixed to one end of one of a pair of feed-rolls crossing said box near its front end at right angles, and between and by which feed-rolls the straw or other material to be cut is fed forward to the knives. The teeth D D, upon spur-wheels C, are cylindrical, and are 55 each provided with anti-friction revolving sleeves E E, which sleeves are retained on said teeth by the loosely overturned or riveted end of said teeth or equivalent means. The worm-wheel F is supported upon and adjustably affixed to axle G by a set-screw, which axle is supported by suitable bearings, H H, affixed to or set into the frame of the cutter-box, and has the wheel B centrally affixed rigidly thereto, by and through which wheel B the driving- 60 power is applied to said feeding and cutting mechanism. The said worm-wheel F is provided with spiral grooves or channels in its periphery passing partially around the wheel, adapted to receive loosely therein the spurs 65 of the wheel C, and to cause said wheel C to be rotated by a part of a revolution while said spurs are in said grooves and as said wheel F revolves. The grooves in the worm-wheel shown in Fig. 3 are provided with such and 70 only so much inclination or pitch as by one-half a revolution thereof to cause the spur-wheel C to perform so much of a revolution as equals the distance from one of its teeth to the next one—that is to say, such inclination that 75 by the one-half of a revolution of said wheel F the spur-wheel C will be caused to make such a part of a revolution that each tooth thereon will at the close of each half-revolution of the worm-wheel, so far as its own position is concerned, be in the exact location that the preceding tooth was in at the beginning of half-revolution of the worm-wheel. This 80 inclination of said groove on wheel F has so much pitch as to carry forward said wheel C 85 the desired distance, while said wheel F is making something less than its half-revolution, and thereafter during the remainder of the half-revolution of said wheel F the wheel C remains at rest, thereby obtaining the 90 intermitting motion required to properly feed the straw to the intermittently-cutting knives, said knives being so adjusted as to cut the straw at the moment when it and the spur- 95 100

wheel C are at rest. By substituting for the wheel F shown in Fig. 3 a wheel having a greater pitch and length of inclination, like the one shown in Fig. 4, the wheel C may be carried forward a distance equal to the distance between two of its teeth by each half-revolution of the worm-wheel, the said worm-wheel being so constructed as to receive and act upon each alternate tooth of said spur-wheel as it revolves, whereby the length of the cut feed will be doubled.

In the foregoing specification the description has been confined to a feed-cutter in which the wheel B is provided with two knives affixed on opposite sides of the wheel; but my mechanism could be as well applied to a cutter having only one knife, or more than two knives, such changes being made in the worm-wheel, by way of change in the pitch and length of inclination of the grooves thereof, as would provide for the forward movement of the straw at such time as the knife is not in contact therewith, which changes would be similar to and such as are indicated by the description

herein of the difference in worm-wheels, Figs. 3 and 4, which changes would readily suggest themselves to any mechanic familiar with worm-wheel mechanism.

Having thus described my invention, what I claim as new, and desire to secure by Letters Patent, is—

In feed-cutters, the frame A, axle G, supported and rotating in bearings H H, said bearings being attached to frame A, knife-carrying wheel B, rigid on axle G, and worm-wheel F upon and rotating with axle G, in combination with spur-wheel C, rigid on the end of one of the feed-rolls, said spur-wheel being provided with cylindrical teeth D D, having anti-friction sleeves E E, substantially as and for the purpose described.

In testimony whereof I affix my signature in presence of two witnesses.

CHS. KNAUER.
